UNITED STATES PATENT OFFICE.

JAMES G. LOWDEN, OF LINCOLN, NEBRASKA.

PISTON-ROD SWAB.

1,258,692.

Specification of Letters Patent. Patented Mar. 12, 1918.

Application filed August 30, 1917. Serial No. 188,897.

To all whom it may concern:

Be it known that I, JAMES G. LOWDEN, a citizen of the United States, residing at Lincoln, in the county of Lancaster and State 5 of Nebraska, have invented a new and useful Piston-Rod Swab, of which the following is a specification.

The present invention relates to a swab for use upon piston rods, valve stems and 10 other reciprocating parts working in packings, and it is the object of the invention to provide such a device constructed to lubricate the rod or stem whereby it will work smoothly in the packing without injuring 15 the packing, as is the case when the rod or stem becomes dry, and the device will also, in being used adjacent to the packing, prevent sand, grit and other foreign matter from reaching the packing.

20 It is the object of the invention to provide a swab of novel construction whereby it can be readily applied to and removed from the rod, and in order that it will effectively carry out its function of supplying lubricant to the rod and cleaning foreign matter therefrom, the device also being simple and inexpensive in construction as well as being efficient and practical in use.

25

With the foregoing and other objects in view, which will appear as the description proceeds, the invention resides in the combination and arrangement of parts and in the details of construction hereinafter described and claimed, it being understood 35 that changes in the precise embodiment of the invention can be made within the scope of what is claimed, without departing from the spirit of the invention.

The invention is illustrated in the accompanying drawing, wherein:

Figure 1 is a view of the swab, partly in elevation and partly in section.

Fig. 2 is a diametrical section on the line 2-2 of Fig. 1, one of the absorbent pads 45 being removed.

Fig. 3 is a view of the device in open position, one of the pads being removed.

The swab is of annular or ring like form to surround the piston rod, valve stem or 50 other part termed hereinafter a rod, for convenience, and the device is divided on a diametrical line and comprises the complementary arcuate sections 1. Each of the sections 1 is composed of the arcuate side plates 2, the arcuate outer and inner walls 3 and 4, and the ends 5 providing a chamber 6 of ar-

cuate form in the section for containing grease, oil or other lubricant. The inner wall 4 and ends 5 of each section are spaced from the corresponding inner edges and ends 60 of the side plates 2, whereby said edges and ends of the side plates provide flanges 7 defining pockets 8 therebetween extending along the ends and inner wall of the section from one end of the outer wall 3 to the other. 65 The ends of the outer walls 3 of the two sections are provided with alining hinge butts 9, and a hinge pin 10 is engaged through one set of hinge butts, to hingedly connect the sections 1, while a latch pin 11 is insertible 70 through the other hinge butts to hold the sections in closed position when they surround the rod. By withdrawing the latch pin 11, the swab can be readily opened and closed in applying or removing it. 75

Pads 12 of suitable absorbent material are seated in the pockets 8 along the inner walls 4 of the sections between the flanges 7, and each pad is preferably formed of elongated strip of absorbent material doubled upon itself, as seen in Fig. 1, and pressed against the wall 4 of the respective section, and the pads can overlap the ends 5 of the sections within the terminals of the pockets. These pads are yieldable and snugly fit the periphery of the rod surrounded by the swab, whereby to clean sand, grit and other foreign matter from the rod, and to also supply lubricant to the rod. One side plate 2 of each section 1 has an aperture 13 for injecting lubricant into the chamber of the section, and said apertures are normally closed by closures 14 pivoted to the respective side plates of the sections. The inner walls 4 of the sections have apertures 15 therein for the flow of lubricant to the pads 12 which absorb the same and supply the lubricant gradually to the rod as it reciprocates. The apertures 15 can be formed by striking the metal into the pockets 8, whereby the spurs 90 thus formed in engaging the pads 12 will assist in holding the pads in place, as well as facilitating the absorption of the lubricant flowing through the apertures from the chambers 6. 105

Having thus described the invention, what is claimed as new is:

1. An annular swab to surround a reciprocating member comprising arcuate sections each having side plates, outer and inner walls and ends, the inner walls and ends being spaced from the inner edges and 110

ends of the side plates to provide pockets, inner walls having apertures for the flow of lubricant into the pockets from said sections, means for holding the sections together, and absorbent pads fitted in said pockets.

2. An annular swab to surround a reciprocating member, comprising arcuate sections each having side plates, outer and inner walls and ends, and forming inclosed lubricant chambers, the inner walls and ends being spaced from the inner edges and ends

of the side plates to provide pockets, the inner walls having apertures for the flow of lubricant into the pockets from said chambers, means for holding the sections together, and absorbent pads fitted in the pockets. 15

In testimony that I claim the foregoing as my own, I have hereto affixed my signature in the presence of two witnesses.

JAMES G. LOWDEN.
